CLAIM

We claim the ornamental design for a suction nozzle for vacuum cleaner, as shown and described.

DESCRIPTION

FIG. 1 is a perspective view of a suction nozzle for vacuum cleaner showing the new design;

FIG. 2 is a front elevation view thereof;

FIG. 3 is a rear elevation view thereof;

FIG. 4 is a left-side elevation view thereof;

FIG. 5 is a right-side elevation view thereof; and,

FIG. 6 is a top plan view thereof.

The broken lines shown in FIGS. 3 and 6 depict portions of the suction nozzle for vacuum cleaner that form no part of the claimed design.
